BUILDING TRIM AND GUTTER STRUCTURE

George E. Vondergoltz, Houston, Tex., assignor to Stran-
Steel Corporation, Houston, Tex., a corporation of
Michigan

Filed Nov. 15, 1967, Ser. No. 9,416

Term of patent 14 years

(Cl. D13—1)

FIG. 1 is a perspective view of a building having the rake trim and gutter structure embodying my design, the view from the opposite direction being substantially the same as this view;

FIG. 2 is an enlarged cross-sectional view taken along line 2—2 of FIG. 1 in the direction of the arrows, and showing the gutter structure;

FIG. 3 is an enlarged cross-sectional view taken along line 3—3 of FIG. 1 in the direction of the arrows, and showing the rake trim; and

FIG. 4 is an enlarged perspective view of a corner of a building having my design showing the area of intersection of the gutter structure and rake trim, with the emblem located at the center peak.

The novel features of my design reside in the portion

shown in solid lines, the broken lines being for the purpose of illustrating a typical building on which such design may be employed.

I claim:

The ornamental design for building trim and gutter structure, as shown and described.
